Primary Examiner — Rhea Shields*(74) Attorney, Agent, or Firm* — Paul D. Bianco; Gary S. Winer; Fleit Gibbons Gutman Bongini & Bianco PL(57) **CLAIM**

The ornamental design for an egg box, as shown and described.

DESCRIPTION

1. Egg box

Figure 1.1: is a top perspective view of an egg box according to the present invention shown in an open position;

Figure 1.2 is a top view of the egg box of Figure 1.1;

Figure 1.3 is a left side view of the egg box of Figure 1.1;

Figure 1.4 is a front view of the egg box of Figure 1.1;

Figure 1.5 is a right side view of the egg box of Figure 1.1;

Figure 1.6 is a back view of the egg box of Figure 1.1;

Figure 1.7 is a bottom perspective view of the egg box of Figure 1.1;

Figure 1.8 is a bottom view of the egg box of Figure 1.1;

Figure 1.9 is a top perspective view of the egg box of Figure 1.1 while in a closed position;

Figure 1.10 is a top view of the egg box of Figure 1.9;

Figure 1.11 is a left side view of the egg box of Figure 1.9;

Figure 1.12 is a front view of the egg box of Figure 1.9;

Figure 1.13 is a right side view of the egg box of Figure 1.9;

Figure 1.14 is a back view of the egg box of Figure 1.9;

Figure 1.15 is a bottom perspective view of the egg box of Figure 1.9; and

Figure 1.16 is a bottom view of the egg box of Figure 1.9.
